UNITED STATES PATENT OFFICE.

CHESTER B. LORD, OF ENDICOTT, NEW YORK, ASSIGNOR TO ENDICOTT JOHNSON CORPORATION, OF ENDICOTT, NEW YORK, A CORPORATION OF NEW YORK.

DESIGN FOR A BOOT.

Application filed March 7, 1927. Serial No. 20,995. Term of patent 3½ years.

To all whom it may concern:

Be it known that I, CHESTER B. LORD, a citizen of the United States, residing at Endicott, in the county of Broome and State of New York, have invented a new, original, and ornamental Design for a Boot, as shown in the accompanying drawing, forming part of the specification.

The drawing shows a perspective view of the boot.

I claim:

The ornamental design for a boot, substantially as shown.

CHESTER B. LORD.
